Black & Beecher,

Steam Vacuum Pump,

N° 9553.

Patented Jan. 25, 1853.

UNITED STATES PATENT OFFICE.

JAMES BLACK AND ORSON BEECHER, OF PHILADELPHIA, PENNSYLVANIA.

IMPROVEMENT IN WORKING THE CONDENSER ATTACHED TO STEAM DIAPHRAGM-PUMPS.

Specification forming part of Letters Patent No. 9,553, dated January 25, 1853.

To all whom it may concern:

Be it known that we, JAMES BLACK and ORSON BEECHER, both of the city and county of Philadelphia, in the State of Pennsylvania, have invented a new and useful Hydraulic Steam-Pump for Raising Water, &c.; and we hereby declare that the same is described and represented in the following specification and drawings.

The nature of our improvement consists in connecting the top of the condenser with the valve-box, between the induction and ejection valves, by a pipe with a check-valve so arranged as to draw the air, &c., from the condenser when the water is drawn down in said pipe by the diaphragm when the vessel is filled with water, and to drive the air out of said pipe through another check-valve into the discharge-pipe or elsewhere by the water when it is forced up in said pipe as it is expelled from the vessel by the steam above the diaphragm, and thus draw the air from the condenser by a column of water working the equivalent of an air-pump; second, in the arrangement of a pipe with a valve in it leading from the bottom of the condenser to the chamber of the pump, so constructed and arranged as to draw the water from the condenser into the chamber of the pump by the action of the diaphragm or its equivalent, thus causing the water-pump to work an exhaust-pump or its equivalent to the condenser at the same time that it does its ordinary work.

To enable others skilled in the art to make and use our hydraulic steam-pump, we will proceed to describe its construction and operation, referring to the drawings above mentioned, in which the same letters indicate like parts in each of the figures.

Figure 1 represents the front; Fig. 2, a section to the right of the line A' B' of Fig. 1; Fig. 3, the openings in the valve-seats; Figs. 4 and 5, the rotating valve.

We construct our pump in the form represented in the drawings, with two globular vessels, A A', each of which is made of two hemispherical cups with openings in the center and flanges at the edges, as represented, to facilitate fastening the two cups together, and at the same time to fasten the flexible diaphragm A², made of vulcanized india-rubber, and shown in Fig. 1, where the vessel A and

diaphragm A² are shown in section cut perpendicularly through the center, the cups on the inside being turned off with a gentle curve where they join the flanges at a a, so as to save the diaphragm from the unnecessary wear to which it would be exposed if the connection of the flange and cup were made with a square corner. The under cup of each vessel is connected to a valve-box, (see A³ A⁵), which boxes have valves in them, so as to receive the water from the branched pipe B, which conducts the water to the pump from the source which supplies it. The water passes from the pump or vessels through the same aperture that it entered, and from the valve-box A⁵ into the valve-box B', and thence into the branched pipe B², which conducts it into the discharge-pipe B³, which conveys it to the required destination. The frame C is fastened to the upper half of each of the vessels, as represented, which frame supports the axis a' of the segment-lever C', the teeth upon the segments making into the racks C² and C³ upon the traverse-rods C⁴ and C⁵, which rods are supported by the friction-rollers a² a³ in the frame C. The traverse-rods pass down through the stuffing-boxes a² a³ into the vessels A A', and are provided with a broad head or washer, a⁴, and a movable washer, a⁵, which is forced down by the nut b, so as to secure the center of the diaphragm A², as represented in the vessel A, Fig. 1. The stop-cocks b¹ b² are opened when necessary to discharge the water which may accumulate above the diaphragms from the condensation of the steam. The steam-pipe D is supported by the bar D', fastened to the flanges of the vessels A A'. A pipe from a steam-boiler is connected to the lower end of D, which conducts the steam into the valve-box D² through the opening b³ in the valve-seat and b⁴ in the valve D³, and it passes from thence through the openings c c² into the pipes c' c³ to the pipes c⁴ c⁵ to the top of the diaphragms in the vessels A A', to force the diaphragms down. The valve D³, turned by the shaft c', allows the steam from the valve-box D² to enter one vessel and force down the diaphragm, while it (the valve D³) allows the steam to escape from the other vessel through the same pipes that conducted in, and to pass out into one of cavities c² c³ in the valve D³, and from thence through the openings c⁴ c⁵

into the exhaust-pipe D^4 and D^6 , and it passes through the pipe D^5 into the condenser E , which surrounds the discharge-pipe B^3 . The pipe E' conducts the water from the discharge-pipe into the condenser E , where the pipe surrounds the discharge-pipe, as represented by dotted lines, and the water escapes through the perforations e to condense the steam, after which it passes or is drawn from the condenser through the pipe D^5 and check-valve d to the valve-box A^5 . A pipe may be attached to the lower end of D^5 to supply the force-pump which feeds the boiler with hot water, which force-pump, we contemplate, may be worked by a lever fastened to the shaft a' . The pipe E' is provided with a cock, d' , to regulate or stop the water from flowing into the condenser. The valve E^2 upon the pipe D^6 is designed to let such a portion or all the steam escape that is not intended to be condensed, in which case the check-valve d might be fastened down and the cock d' turned so as to supply sufficient water to feed the boiler; or it may be supplied from some other source. The air and uncondensed steam is drawn from the condenser E through the valve d^2 by the descent of the water in the pipe E^3 when the diaphragm A^2 is raised, and when it descends the water is forced up in the pipe E^3 and drives the air through the valve d^3 and pipe d^4 into the discharge-pipe B^3 , as the valve d^4 prevents it from entering the condenser again. A portion of the pipe d^4 and the valve d^4 are shown in section, (enlarged in Fig. 6.) The valve-shaft e' turns in the stuffing-boxes F F' , fitted to the projections upon the valves box D^2 , and is operated in part by the lever F^2 , fastened to it and connected by the rod F^3 to the lever F^4 upon the shaft a' , which is moved by the segments acted upon by the racks C^2 C^3 . The sector G is fastened to the shaft e' , which is moved by the lever F^2 , as above mentioned, until the sector G carries the lever G^2 and ball G^3 so far past a perpendicular from the center of the shaft e' that the ball G^3 falls and carries the sector and shaft e' , moving the valve D^3 , so that the cavity e^3 covers the openings e and e' , and permits the steam to pass from the pipe e' into D^4 , and at the same time allows the steam to pass from D through b^3 and c^2 into c^3 , the cavity e^2 covering e^3 , the slot f in the rod F^3 permitting the lever F^2 to be moved by the falling of the ball G^3 above mentioned.

The hydraulic steam-pump having been constructed and completed as above described, and a suction and discharge pipe properly attached thereto, or if the pump is placed so low that the water will flow into it a supply instead of a suction pipe may be attached to the branch pipe B , also a supply-pipe from a steam-boiler connected to the pipe D , and a supply of steam let into the valve-box D^2 , passing therefrom through the pipe c' into the vessel A , forcing down the diaphragm A^2 and rod C^4 , driving the water from A into the valve-box below, and thence opening a valve simi-

lar to H , (represented in dotted lines in B' ,) it flows through the branched pipe B^2 and discharge-pipe B^3 to its destination. When the diaphragm A^2 and rod C^4 descend, they work the lever C' , and draw up the rod C^5 and diaphragm connected to it, drawing the water into A' through the valve H' . At the same time the air or steam above the diaphragm in A' passes through the pipe c^3 , valve-box D^2 , and pipes D^6 , D^4 , and D^3 into the condenser E . As the lever C' is vibrated, as above mentioned, it carries up the lever F' , rod F^6 , lever F^2 , turning the valve D^3 , so as to shut the steam from the pipe C' , and at the same time it moves the sector G , so as to carry the lever G^2 and ball G^3 so far past the perpendicular from the center e' that the ball falls on the opposite side, carrying the sector with it and moving the valve D^3 , so as to let the steam into the vessel A' , and force the diaphragm and rod C^5 down, driving the water out of A' through the valve H and pipes B^2 and B^3 to its destination. When the rod C^5 is carried down, it works the lever C' and draws up the rod C^4 and diaphragm A^2 , forcing the steam from A through c' , D^2 , D^4 , and D^3 into the condenser E , the valve D^3 being turned by the ball G^3 when it falls, so as to allow it to escape, and at the same time shuts the steam from the pipe c^3 and places the valve so as to let the steam into A and allows it to escape from A' , as heretofore described. If it is desirable to work the pump and condense only a part of the steam, the balance may escape through the valve E^2 ; or by removing the valve the pump may be worked without condensing at all, when it will be necessary to supply the feed-pipe for the boiler from some other source than the pipe D^6 . When the diaphragm A^2 is forced down, it raises the water in the pipe E^3 and drives the air from the pipe through the valve d^3 , and when the diaphragm is raised it draws the water out of said pipe, and the air, &c., from the condenser, through the valve d^2 , and when the diaphragm is forced down again the air, &c., is driven through the valve d^3 , as before mentioned, and may be made to enter the discharge-pipe through d^4 , or otherwise. Thus the diaphragm causes the column of water to work the equivalent of an air-pump to the condenser. When the diaphragm in the vessel A' is raised, it draws the water from the condenser through the pipe D^5 and valve d , thus causing the diaphragm to work an exhaust-pump to the condenser.

We contemplate that the diaphragms may be made of such other materials besides that above mentioned as will answer the purpose, and fixing a fulerum for the lever G^2 below the valve-shaft, so as to relieve the valve from the jar of the ball G^3 when it falls.

We are confident that a pump can be constructed, as above described, to raise a given quantity of water in a stated time for one-fourth of the cost of a common piston-pump and steam-engine to operate the same, and that our pump will raise a given quantity of

water to a stated height with half the steam or power required to operate a piston-pump and steam-engine to raise the same quantity of water to the same stated height. Consequently we should save fifty per cent. in the cost of boilers and fuel required and seventy-five per cent. of the cost of an engine and piston-pump to do the same amount of work.

What we claim as our invention, and desire to secure by Letters Patent, is—

1. The pipe E³ and valves d² and d³, or their equivalents, so constructed and arranged as to draw the air, &c., from the condenser and drive it into the discharge-pipe or elsewhere by the column of water in said pipe, operated by the working of the diaphragm, which causes said column of water to work the equivalent of an air-pump to the condenser.

2. The pipe D⁵ and valve d, or their equivalents, so constructed and arranged as to draw the water from the condenser by the raising of the diaphragm, thus causing the water-pump to work an exhaust-pump or its equivalent to the condenser at the same time that it does its ordinary work, substantially as described.

In testimony whereof we have hereunto signed our names before two subscribing witnesses.

JAMES BLACK.
ORSON BEECHER.
